UNITED STATES PATENT OFFICE

120,868

DESIGN FOR A DISPENSING DEVICE OR SIMILAR ARTICLE

Anthony Marra, Flower Hill, N. Y.

Application March 6, 1940, Serial No. 90,724

Term of patent 3½ years

To all whom it may concern:

Be it known that I, Anthony Marra, a citizen of the United States, residing in the village of Flower Hill, county of Nassau, and State of New York, have invented a new, original, and ornamental Design for a Dispensing Device or Similar Article, of which the following is a specification, reference being had to the accompanying drawing, forming part thereof.

I claim:

The ornamental design for a dispensing device or similar article, as shown.

ANTHONY MARRA.
